(57) **CLAIM**

The ornamental design for a tyre, as shown and described.

DESCRIPTION

FIG. 1 is a front, left side perspective view of a tyre showing our new design;

FIG. 2 is a front elevation view thereof;

FIG. 3 is a left side view thereof, the right side view being the mirror image thereof;

FIG. 4 is an enlarged fragmentary front elevational view thereof;

FIG. 5 is an enlarged fragmentary front view showing a circumferential channel; and,

FIG. 6 is an enlarged fragmentary front view showing a channel between circumferentially adjacent left side cleats.
